AUTOMATIC STOPPING AND STARTING ATTACHMENT FOR PHONOGRAFS

Filed Apr. 8, 1922

Fig. 1.

Inventor:
Frederick E. WARTH

By *Robert T. Tator*,
Attorneys.

Patented Feb. 27, 1923.

UNITED STATES PATENT OFFICE.

FREDERICK E. WARTH, OF SAVANNAH, GEORGIA, ASSIGNOR OF ONE-HALF TO
MORTON DEUTSCH, OF SAVANNAH, GEORGIA.

AUTOMATIC STOPPING AND STARTING ATTACHMENT FOR PHONOGRAHS.

Application filed April 8, 1922. Serial No. 550,710.

To all whom it may concern:

Be it known that I, FREDERICK EMIL WARTH, a citizen of the United States, residing at Savannah, in the county of Chat-
ham and State of Georgia, have invented or
discovered certain new and useful Improve-
ments in Automatic Stopping and Starting
Attachments for Phonographs, of which the
following is a specification, reference being
had therein to the accompanying drawing.

This invention relates to an automatic
stopping device for phonographs of that
class carrying disk records, and has for its
object to provide a device of simple con-
struction whereby when the end of the record
is reached the rotation of the turn-table bearing
the record will be automatically stopped
by a brake applied thereto, and which brake
will be released when the tone arm is swung
outward or reset for the next operation. To
this end the invention comprises a pinion
carried by the shaft of the turn-table which
carries the record, said pinion meshing with
a gear wheel provided with a resetting cam
and a scroll cam. Frictionally attached to
the base of the tone arm is a band which is
suitably connected to the rear arm of a lever
carrying at its forward end a pin to be en-
gaged, at proper times, by the said resetting
cam and scroll cam, said lever controlling a
brake device which, through the action of
said scroll cam and lever, will be thrown
into contact with the periphery of the record-
carrying turn-table to stop the rotation of
the latter when the end of the record has
been reached, all as will hereinafter more
fully appear.

In the accompanying drawing Fig. 1 is a
plan view of a preferred embodiment of the
present invention, and Fig. 2 is a side view
of the same.

Referring to the drawing, 12 denotes a
turn-table, adapted to carry a disk record
and 13 is a rotating shaft to be operated by a
spring motor in the usual manner and to
which shaft said turn-table is fixed. Also
fixed to the shaft 13 is a pinion 14 meshing
with a gear wheel 15 provided with a scroll
cam 16 and with a resetting cam 17.

Attached to the upright part 18 of the
tone arm 18^a is a friction band 19, which,
by means of an adjustable screw 20, may
be made to embrace the said upright part
of the tone arm with any desired degree of
tightness. Carried by the friction band 19

is a lug 21 having a slot 22. Pivoted to the
table of the phonograph, as by screw 23, is
a lever 24 provided at its rear end with a
pin 25 received loosely in a slot 22 in the
lug 21, said lever having at its forward end 60
a depending pin 26 to be engaged at times by
the scroll cam 16 and resetting cam 17. Piv-
otally attached to the lever 24 is a brake
lever 27 carrying at one end a suitable brake
28. One arm of the said brake lever is con- 65
nected by a spring 29 with the said lever 24,
said spring normally tending to hold the said
brake arm in yielding contact with a stop
30 fixed to the said lever 24. The other arm
of said brake lever is extended rearward so 70
that it may, at a proper time, be engaged
by a lug or projection 31 on the base or up-
right portion 18 of the tone arm 18^a.

The operation of the machine is as fol-
lows: When the turn-table 12, carrying the 75
disk record, is in rotation the tone arm will
move inward slowly over the record in the
usual manner. The rotation of the turn-
table shaft 13, carrying the pinion 14, will
cause a slower rotation of the gear-wheel 15 80
carrying the cams 16 and 17. The slow
turning movement of the base portion 18 of
the tone arm will impart a corresponding
movement to the friction band 19 carrying
the lug 21. When the lower wall of the slot 85
22 in the lug 21 (looking at Fig. 1) is in en-
gagement with the pin 25 near the rear end
of the lever 24 the said lever will be held in
contact with a fixed stop pin 32 on the pho-
nograph table, and in this position of said 90
lever the pin 26 carried by said lever will
be engaged by the resetting cam 17 when,
in the rotation of the gear-wheel 15, said
cam comes opposite said pin. This engage-
ment of said cam 17 with the pin 26 will 95
move the longer arm of said lever 24 in-
ward slightly away from the stop pin 32,
causing the pin 25 on the shorter arm of
said lever, through the lug 21, to turn the
friction band 19 slightly on the upright por- 100
tion 18 of the tone arm 18^a in a direction
opposite the turning movement of the tone
arm, thus moving the forward or longer arm
of the lever 24 away from the stop pin 32,
and far enough inward so that the pin 26 105
would be in a position to be engaged by the
scroll cam 16 at the next rotation of the gear
wheel 15 if said lever remained in the posi-
tion to which it is thus turned by the said
resetting cam. But as the tone arm will 110

2 still continue to move inward over the disk record until the reproduction of said record is completed, the slow turning movement of the friction band 19 with the tone arm will 5 gradually, by the lug 21 and pin 25, and during the next rotation of the gear wheel 15, return the lever 24 to its former position in contact with the stop pin 32, thus carrying the pin 26 out of range of the scroll cam 10 16. This operation will be repeated during the reproduction of the record, but when the end of the record has been reached and the turning movement of the tone arm ceases, the lever 24 will remain in the inward position, 15 to which the resetting cam 17 last moved it, and in this inward position the pin 26, carried by said lever will be in position to be engaged by the scroll cam 16 when said scroll cam next reaches said pin 26. This 20 engagement of the said scroll cam with said pin, as the gear wheel 15 continues to rotate, will impart a movement to the lever 24, to a position at or near the pin 33, and sufficient to bring the brake 28, moving with said lever, into contact with the periphery of the turn-table and thus arrest the movement thereof. When the machine is to be again started and the tone arm is moved outward over the disk record the lug or projection 31 25 on the upright part of said tone arm will engage the tail of the brake lever 27 and thus release the brake from the turn-table. Thus it will be understood that the invention provides an efficient automatic brake mechanism 30 by which the rotation of the record-carrying turn-table will be arrested when the reproduction of the record has been completed, the construction being such that the brake will be released, to permit the machine 35 to start again, when the tone arm is reset to repeat the reproduction of the record or to play a new record.

Having thus described my invention I claim and desire to secure by Letters Patent:

1. An automatic stopping attachment for phonographs consisting of the combination with a wheel geared to the turn-table shaft and provided with a scroll cam, of a lever 50 having at its forward end a pin to be engaged, when desired, by said cam, a brake device connected with said lever and adapted to be moved into contact with the turn-table, and means, connected with the tone arm, whereby when the reproduction of a record has been completed said pin will be moved into a position to be engaged by said scroll cam and thereby, through said lever, move the brake device into contact with the turn-table to arrest the movement of the latter.

2. An automatic stopping attachment for phonographs consisting of the combination with a wheel geared to the turn-table shaft 65 and provided with a scroll cam and a re-

setting cam, of a lever having at its forward end a pin to be engaged, when desired, by said cams, a brake device connected with said lever and adapted to be moved into contact with the turn-table, and means, connected with the tone arm, whereby when the reproduction of a record has been completed said pin will be moved into a position to be engaged by said scroll cam and thereby, through said lever, move the brake device into contact with the turn-table to arrest the movement of the latter.

3. An automatic stopping attachment for phonographs consisting of the combination with a pinion to be mounted on the turn-table shaft, of a wheel geared to said pinion and carrying a scroll cam and a resetting cam, a lever having a pin to be engaged, when desired, by said cams, a brake device connected with said lever and adapted to be moved into contact with the turn-table, a friction band to be yieldingly mounted on the base portion of the tone arm and means connecting said friction band with the rear arm of said lever; whereby, during the reproduction of a record, the said pin will be prevented from being engaged by said scroll cam until the reproduction of the record has been completed and will then be in a position to be engaged by said scroll cam so that the said brake device will be moved into contact with the turn-table to arrest the movement of said turn-table.

4. An automatic stopping device for phonographs consisting of the combination with a pinion to be mounted on the turn-table shaft, of a wheel geared to said pinion and carrying a scroll cam and a resetting cam, a lever having a pin to be engaged, when desired, by said cams, a brake lever pivoted on said first-named lever and carrying a brake-member adapted to be moved into contact with the turn-table, a friction band to be yieldingly mounted on the base portion of the tone arm, and means connecting said friction band with the rear arm of said lever; whereby, during the reproduction of a record, the said pin will be prevented from being engaged by said scroll cam until the reproduction of the record has been completed and will then be in a position to be engaged by said scroll cam so that the said brake member will be moved into contact with the turn-table to arrest the movement of said turn-table.

5. An automatic stopping attachment for phonographs consisting of the combination with a pinion to be mounted on the turn-table shaft, of a wheel geared to said pinion and carrying a scroll cam and a resetting cam, a lever having at its forward end a pin to be engaged, when desired, by said cams and having a second pin at its rear end, a brake lever pivotally mounted on said first-named lever and carrying a brake member

- adapted to be moved into contact with the turn-table, and a band to be frictionally mounted on the base portion of the tone arm and provided with a lug having a slot entered by said last-named pin, and a projection movable with the tone arm and 30
5 tered by said last-named pin; whereby, during the reproduction of a record, the said pin at the forward end of said lever will be prevented from being engaged by said scroll cam until the reproduction of the record has
10 been completed and will then be in a position to be engaged by said scroll cam so that said brake member will be moved into contact with the turn-table to arrest the movement of said turn-table.
- 15 6. An automatic stopping and starting attachment for phonographs consisting of the combination with a pinion to be mounted on the turn-table shaft, of a wheel geared to said pinion and carrying a scroll cam and a
20 resetting cam, a lever having at its forward end a pin to be engaged, when desired, by said cams and having a second pin at its rear end, a brake lever pivotally mounted on said first-named lever, and carrying a
25 brake member adapted to be moved into con-
- tact with the turn-table, a band to be frictionally mounted on the base portion of the tone arm and provided with a lug having a slot entered by said last-named pin, and a projection movable with the tone arm and 30
35 arranged to engage said brake lever when desired; whereby, during the reproduction of a record, the said pin at the forward end of said lever will be prevented from being engaged by said scroll cam until the reproduction of a record has been completed and will then be in position to be engaged by said scroll cam to move said first-named lever a sufficient distance so that said brake member will be forced into contact with the 40
45 turn-table to arrest the movement of said turn-table; and whereby, also, when the tone arm is reset for a new operation, the said projection, movable with said tone arm, will engage the said brake lever and release said brake member from said turn-table to enable the machine to start.

In testimony whereof I affix my signature.

FREDERICK E. WARTH.
